CLAIM

The ornamental design for the bezel rim for a vehicle wheel, as shown and described.

DESCRIPTION

FIG. 1 is a front view showing my new bezel rim for a vehicle wheel;

FIG. 2 is a rear view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of my new bezel rim for a vehicle wheel; and,

FIG. 8 is a perspective view of my new bezel rim for a vehicle wheel with a tire mounted upon it.

The broken lines are for environmental purposes only and form no part of the claimed design.
